UNITED STATES PATENT OFFICE.

ALPHEUS E. ROE, OF SAN FRANCISCO, CALIFORNIA, ASSIGNOR TO TATUM & BOWEN, OF SAME PLACE.

CRUSHING-MILL.

SPECIFICATION forming part of Letters Patent No. 380,821, dated April 10, 1888.

Application filed September 21, 1887. Serial No. 250,358. (No model.)

To all whom it may concern:

Be it known that I, ALPHEUS E. ROE, of the city and county of San Francisco, State of California, have invented an Improvement in 5 Crushing-Mills; and I hereby declare the following to be a full, clear, and exact description of the same.

My invention relates to certain improvements in crushing-mills which are especially 10 adapted for crushing the ores of valuable metals.

It consists of two or more heavy weights having a series of stamps fitted into their lower convex faces, and dies upon which these stamps 15 operate, together with a mechanism whereby the two series of oscillating stamps may be caused to move in opposite directions within the same mortar.

It also consists in an improved method of 20 discharging the pulverized ore, as will be more fully explained by reference to the accompanying drawings, in which—

Figure 1 is a longitudinal vertical section through the mortar, showing the two sets of 25 crushing devices and the driving mechanism and discharge. Fig. 2 is a transverse vertical section of the same.

A and B are two heavy blocks of metal, having the lower faces rounded or curved in the 30 arc of a circle; and a are projecting rubbing plates or blocks upon their sides to steady them and keep them apart when they are in place and at work in the mortars. In these curved faces are fitted stamps C in such a 35 manner that their lower or crushing faces extend in a similar curved arc; and D are dies placed in the bottom of the mortar E, so that ore or material fed into this mortar will be crushed between the opposing surfaces.

40 In order to increase the crushing capacity of my apparatus and make the work more continuous and complete, I have mounted the crushing devices A and B side by side in a single mortar, which is made of sufficient width 45 to accommodate the two. From the upper ends of the weighted crushers A and B vertically-slotted extensions F project, the slots G forming guides within which the crank-pins H and I project, these crank-pins having rotat-

ing loosely-fitted sleeves upon them, which reduce the friction as the pins travel in the slots, by reason of the rotation of the disks to which they are attached.

J is the driving-shaft, through which power is applied to actuate these stamps, and upon 55 the end of the shaft J, adjacent to the inner stamping device, is fixed a disk, K, and the crank-pin H projects from this disk, extending through the slot G, and having its outer end fixed in a disk, L, which lies between the 60 two slotted extensions F, as shown in Fig. 2. From a point in the disk L opposite the pin H the pin I passes through the slot of the second or outer crushing device, A, and its outer end is fixed in a similar disk, M. The center of 65 this disk is securely keyed to a short shaft, N, and this shaft turns in a journal-box, O, which is in line with the box P, in which the end of the shaft J turns. By this construction it will be seen that the intermediate disk, L, is supported in place by means of the crank-pins 70 H and I upon opposite sides of its center, and through this disk and these pins connection is made with the outer disk, M, which, being journaled upon the short shaft, gives a 75 support for the outer end of the driving mechanism.

The ore is fed into the mortar beneath the stamps by any suitable feeding device, and I have shown the discharge-openings Q in the 80 present case made in the ends of the mortar in line with the crushing-stamps. The alternate oscillations of the stamps will first throw the ore alternately from one side of the crushing dies and stamps to the other, thus greatly 85 increasing the effectiveness of the mill, and the motion of the stamps also tends to throw the ore toward the ends of the mortar, so that when sufficiently pulverized it passes through the screens in the discharge-openings more 90 readily than it would do if these discharge-openings were placed upon the sides.

Having thus described my invention, what I claim as new, and desire to secure by Letters Patent, is—

1. The combination of the mortar, the oscillating stamps having the vertically-slotted extensions at the upper ends, as shown, the driving-shaft having the disk or crank fixed upon its end, and an outer disk or crank having a 95

short shaft journaled in line with the driving-shaft, in combination with a similar disk intermediate between the slotted extensions of the blocks, and crank-pins extending through 5 the slots of the two blocks from opposite sides of the intermediate disk, so that power is communicated to drive the two from the single shaft, substantially as herein described.

2. A crushing-mill comprising a single mortar having discharge-openings in its ends, a plural number of oscillating blocks having projecting stamps, and a driving-shaft having

crank-pins connected with said blocks and operating the blocks in opposite directions, whereby the ore is thrown alternately from 15 one side of the stamps to the other, substantially as and for the purpose described.

In witness whereof I have hereunto set my hand.

ALPHEUS E. ROE.
